J. A. Montgomery

UNITED STATES PATENT OFFICE.

J. A. MONTGOMERY, OF WILLIAMSPORT, PENNSYLVANIA.

IMPROVED CANTEEN.

Specification forming part of Letters Patent No. 33,360, dated September 24, 1861.

To all whom it may concern:

Be it known that I, J. A. MONTGOMERY, of the borough of Williamsport, in the county of Lycoming and State of Pennsylvania, have invented a new and useful Improvement in Canteens for Carrying Water or other Liquids; and I do hereby declare that the following is a full, clear, and exact description of the construction and operation of the same, reference being had to the annexed drawings, making a part of this specification, in which—

Figure 1 is a plan view of the canteen closed; Fig. 2, a plan view of the canteen with funnel in place; Fig. 3, a transverse section of the canteen as closed; and Fig. 4, a plan view of the funnel used as a cup, in all of which figures the same letters so often as they occur refer to the same parts.

A represents the body of the canteen; B, the funnel or cup; C, the nozzle or neck of funnel; D, the cork or stopper; E, a flat metallic top to cork; F, a closed nipple on the funnel; H, an open nipple on the canteen to allow the egress of air when the canteen is being filled; J, the neck of the canteen.

To enable others to make and use my invention, I will proceed to describe its construction and operation.

I construct a canteen of any desired form and of any desired material. I then construct a cup fitting over a portion of the canteen and with a neck fitting over the neck of the canteen, capable of being removed from the canteen, and which, when reversed and again as reversed placed on the canteen, forms a funnel, as shown in Fig. 2, and which funnel, when removed from the canteen, will form a cup, as shown in Fig. 4.

What I claim as my invention, and desire to secure by Letters Patent, is—

A canteen of any desired form or material, with a funnel or cup fitting it, substantially as described.

J. A. MONTGOMERY.
